UNITED STATES PATENT OFFICE.

WARREN H. FROST AND JOSHUA J. NIX, OF LOS ANGELES, CALIFORNIA; SAID NIX ASSIGNOR
TO SAID FROST.

PROCESS OF PRODUCING GAS.

No. 900,065.

Specification of Letters Patent.

Patented Sept. 29, 1908.

Original application filed February 18, 1907, Serial No. 358,152. Divided and this application filed October 22, 1907.
Serial No. 398,655.

To all whom it may concern:

Be it known that we, WARREN H. FROST and JOSHUA J. NIX, citizens of the United States, residing at Los Angeles, in the county 5 of Los Angeles and State of California, have invented a new and useful Process of Producing Gas, of which the following is a specification.

This invention relates particularly to the 10 production of gas for use in internal combustion engines, although the gas may be used for other purposes.

The main object of the present invention is to produce gas from hydrocarbon oils in a 15 continuous manner by internal combustion.

Another object of the present invention is to dispense with the necessity of any storage tanks.

Another object of the invention is to provide 20 for the production of gas of uniform quality or composition.

Another object of the invention is to provide for the production of gas having a 25 larger proportion of fixed hydrocarbon gases than is the case with ordinary producer gas.

Another object of the invention is to provide 30 for automatic regulation of the gas production for fluctuations in the demand.

The present process is distinguished from 35 those processes using retorts, in that the heat for production and fixation of the gas is generated internally, that is to say, in the same chamber or space which contains the hydrocarbon to be gasified, so that the heat does not have to be transmitted through the 40 walls. Said retort processes are not suitable for the production of gas from heavy hydrocarbons, in that the accumulation of residuum and deposits interferes seriously 45 with the continuity and economy of the process and with the uniformity of the gas, and also in that the expense of such production is prohibitive. The process of the present invention is also distinguished from

50 those processes involving internal combustion intermittently with the gas generation, the heat being applied to and stored in a chamber or body and the generation of the heat being then stopped and shifted to another point and the gas being generated by applying the oil to the chamber or body so heated. In this intermittent or alternate process the quality of the gas necessarily varies during each stage, as the temperature of

the chamber or heating body rapidly falls 55 and the character of the generated gas varies with the falling temperature. This variation is equalized in practice by the use of storage tanks or gasometers in which the varying constituents are allowed to mix before 60 consumption.

The present invention provides for a continuous generation at uniform temperature and thereby produces gas of uniform quality or composition and dispenses with the necessity of any storage tank means. According to the present invention gas is generated by passing the oil, or the vapor formed by atomizing oil, into or through a heating zone which is kept continuously at a high temperature by supplementary heating means or burners, the reaction or mutual action of the oil and of the gaseous contents of the heating zone being such as to produce a permanent gas. These operations are performed 70 in a chamber which is open to communication with the outer air, and is connected at its upper portion to a suction means continuously drawing the produced gas from the chamber. 80

While we have herein shown apparatus for carrying out the process, such apparatus is not claimed herein, being claimed in our application Serial No. 358,152, filed Feb. 18, 1907, of which this application is a division. 85

The process is carried out in the apparatus shown in the accompanying drawings, wherein:

Figure 1 is a vertical section of the apparatus partly in elevation. Fig. 2 is a horizontal section on the line x^2-x^2 in Fig. 1. Fig. 3 is a section on the line x^3-x^3 in Fig. 1. Fig. 4 is a side elevation. Fig. 5 is a detail side elevation of the generator feed or supply. Fig. 6 is an end elevation thereof. Fig. 7 is a front elevation of the heating burner. Fig. 8 is a horizontal section thereof. 95

The apparatus comprises a furnace or generator 1 preferably formed of masonry or other heat-resisting material and formed with an interior vertical chamber 2 and a flue 3 leading upwardly therefrom to a discharge outlet at the top of an outlet conduit 4, having an upwardly inclined extension 5 into a stack 6. Said stack is provided with a closure valve 7, and an aspirator 8 is connected to the stack or to the outlet flue 5 to draw the gas therefrom into de- 100 105

livery pipe 12, as hereinafter set forth, said aspirator being actuated by water supplied by pipe 9.

- 5 Heating burners 10, of which there may be any desired number, are provided, discharging inwardly into the chamber 2, said burners being provided with air and oil supply means, as hereinafter set forth, and having outlet means or jet pieces 11, whose openings 10 are directed obliquely downward toward the center of the chamber 2 so that the jets issuing from said openings, will meet in the interior of the chamber 2. The walls of the generator are formed with passages 13 extending inwardly from these heating burners to the chamber 2 to permit of the passage of the jets therefrom to the chamber. The burners or the adjacent portions of the chamber walls are formed with openings 14, 15 for the admission of air, so that the chamber is open to communication with the outer air so that air is allowed to enter the chamber at substantially atmospheric pressure. The burners 10 discharge into the chamber 2 20 near enough to the bottom thereof to keep the bottom well heated, avoiding deposition of carbon thereon.

Means are provided for supplying oil, or a mixture of oil and air suitable for the gas 30 to be produced, below the flame or flames from the burner or burners 10, said means consisting of an inlet pipe 15 extending through the wall of the generator and connected to an oil feed as hereinafter described, 35 to furnish a supply of atomized oil, together with air, to the lower part of the chamber 2. The said supply means for this outlet, shown in Figs. 5 and 6, comprises an oil supply pipe 17, a chambered fitting 18 connected to 40 said oil supply pipe by a connecting member 19, a glass or transparent tube 20 connecting said oil supply pipe with the chamber 21 in said fitting so as to produce a sight feed for the supply, and an air supply pipe 45 22 having a nozzle 23 extending into said chamber to produce an injector effect therein, the walls of said chamber being narrower at 24 to accentuate said injector effect and cause the mixture of air and atomized 50 oil to pass into the inlet pipe 15.

The upper portion of chamber 2 preferably converges upward to its outlet into flue 3, and said flue may be swelled or enlarged to form a supplementary chamber and may 55 be provided with baffles in the form of checker work or fire brick obstructions 25 extending across the same to deflect the upwardly passing gases and cause more thorough mixture.

60 26 designates a door, plug or other means in the wall for giving access to the chamber 2 in starting up, etc.

In order to heat the oil before it passes to the burners and also in order to cause preliminary separation of the oil, as far as pos-

sible, in the manner hereinafter set forth, the tank 27 for containing the oil supply is placed on or near the generator or furnace in such position as to receive the heat therefrom, for example, being placed thereon 70 around the outlet flue 4, so that the hot gases pass upwardly through said flue and heat said tank. 28 designates the oil supply pipe to this oil tank and 53 a plug for drawing off residuum.

29 designates the oil outlet pipe leading from the lower part of the tank through pipes 30 and valves 31 to the heating burners 10. A pipe 34 leads from the upper part of the tank 27 to the supply 17 for the generator burner, and is provided with a valve 33 operated by connections 37 from a governor 38 on the engine 39 which is supplied with gas from the producer. A connection is made from the delivery pipe 12 through suitable scrubbing means 57, see Fig. 4, to the inlet 55 for the engine. A manual valve may also be provided for the oil supply. The connections 37 may also operate a valve 33 controlling the air supply to the mixture 90 inlet. The suction of the engine 39 at each intake stroke tends to draw the gas through the connections between the producer and the engine through the scrubber 57, and thereby aids in maintaining the passage or 95 supply of air and combustible to the gas generating chamber. The air supplied to the heating burners is preferably heated by the exhaust from said engine, pipe 32 for said air supply passing around said exhaust 100 and communicating through the valve 40 with pipe 42 for the said burners. This air is supplied at a considerable pressure generated by any suitable means, such as a pump not shown. While various forms of 105 heating burners may be used in connection with the apparatus, that shown in Figs. 7 and 8 is especially designed for this purpose, the burner head 11 being attached to a plate 43 secured to the wall of the generator chamber, said plate having openings 44 for the passage of air extending obliquely therethrough so as to converge toward the burner jet opening 45 which is formed in a head or nozzle 11 projecting from the base 115 of a conical depression 46 in said plate. Damper means consisting of a plate 47 is adjustably secured on the supporting plate 43 by means of screws 48 extending through slots 49 on said damper plate, the said 120 damper plate having perforations 50 to register more or less with the openings 44 in the supporting plate. In order to enable quick adjustment, for example, on stopping the engine, means are provided for indicating accurately the degree of opening of the damper, such means consisting of an index or pointer 51 on the damper moving over a fixed graduated scale 52. Pipe 42 opens laterally into an outer pipe 64 screwing 130

onto the outer end of burner nozzle 11. Said nozzle has a bore 55 smaller than pipe 54. The oil supply pipe 29 extends into the end of pipe 54 beyond the opening of pipe 42. 5 The process is carried out in the above described apparatus as follows:—Closure or valve 7 in the stack is opened and the heating burners 10 are turned on and ignited, the jets in said burners extending into the 10 chamber 2, heating the same, and the hot gases passing up through the flue 3 and out through the stack. When the chamber 2 has thus become thoroughly heated, the damper 7 in the stack is closed, the aspirator 8 is 15 turned on so as to draw the gases downwardly through the delivery pipe 12 to any suitable consumption means, for example, the engine 39 or service pipes not shown; and the valves 40, 31 for the mixture of producing supply means are turned on, causing a supply of atomized oil together with just sufficient air to carry the same is thereby blown into the lower part of the chamber 2. 20 The two jets from the opposite burners 10 meet in the middle of the furnace, and by their impingement and opposition mutually arrest each other and produce a zone or layer of intensely heated gases extending across the chamber at a level between the 25 lower and upper portions thereof and above the intake of the producing mixture. The mixture is applied under the pressure of, say 20 pounds to the square inch, and the same is true of the oil, and this together with the 30 suction by the aspirator and the suction of the engine or consuming means, causes a flow of the producing mixture upwardly through or into this high temperature zone. The chamber 2 is open to the outer air 35 through the openings 44, and the air compressed and forced in with the oil is not sufficient to support combustion, the oil so carried in burning in the open chamber and the combustion being supported by the air 40 passing through openings 44 and the combustion thus takes place in the presence of air at substantially atmospheric pressure. We thus insure complete combustion of the oil and maximum temperature of the heating 45 flame, without compression of more than a small part of the air and with a correspondingly great economy. The suction of the products of combustion, from the top of the chamber, by the engine and the aspirator, keeps the products of combustion away 50 from the incoming combustible and air, thus aiding in maintaining perfect combustion at the heating burners. The condition of suction maintained in the chamber is also of advantage, as compared with a condition of 55 pressure, for mechanical reasons, in preventing leakage and reducing the strains on the parts of the furnace.

In the above described construction the interior of the chamber is clear or free of solid

obstructions, such as brick or checkwork, in the path of the jets. Consequently there is no liability of deposition of carbon on solid surfaces. This is further insured by the fact that each of the heating jets is impinged by 70 an opposing elastic fluid jet (namely, the other burner jet) which arrests it in the interior of the chamber, and prevents it from impinging on the opposite wall. The vertical disposition of the chamber is also of importance in this connection as it permits of the jets being arranged in this manner. 75

The baffle devices 25 in the outlet flue are for the purpose of insuring more thorough mixture of the gases and complete combustion. By proper adjustment of the heating burners and producing inlet valves, it is possible to maintain continuity of the process for an almost indefinite length of time, producing gas of uniform quality ready for 80 instant delivery to the service or consumption means without having to be stored or mixed. For this reason and also for the very fact that the process is continuous, the capacity of the plant is large compared with 85 one of the same size using the intermittent process. 90

It will be noted that the oil is supplied to the oil tank at a point between the upper and lower portions thereof and that the outlet to the heating burners is from the lower portion, and the outlet to the producing inlet is from the upper portion. When oils of high gravity are heated, there is a tendency 95 for the heavier constituents to settle and these will pass down to the heating burners, whereas the more volatile constituents will have a tendency to pass through the upper outlet and thence to the producing inlet. This is of advantage in that the heating 100 burners are more capable of utilizing the heavier constituents, whereas such constituents could not be so advantageously utilized in the producing inlet, as they could not be so satisfactorily atomized in the manner required. Any volatile constituents of the oil 105 will pass off at the top along with the lighter oil and will form part of the producing mixture. Actual residuum which is not suitable for burning, collects in the oil tank 22 below 110 the outlet to the heating burner and may be drawn off from time to time by the plug 53.

In case of fluctuating demand, means are provided for varying the gas production in correspondence with the fluctuations. This 115 is necessary for the reason that this invention dispenses with the use of a storage tank and therefore it is necessary to cut down or increase the supply in response to the diminishing or increasing demand. For example, 120 in case of a producer used in connection with a gas engine, it is necessary to reduce or increase the supply in accordance with the demands of the engine, and for this purpose the connection from the engine governor to 125 130

the oil supply for the producing inlet is provided as above described.

The upwardly inclined extension 5 of the outlet, leading to the stack, is found to be 5 desirable to securing the proper draft, both in starting the draft into the stack and in maintaining it by the aspirator.

When the producer is used in connection with a gas engine we prefer to make the 10 capacity of the chamber 2 correspond, roughly speaking, to the capacity of the engine cylinder, the throat or outlet portion 3 being in that case of such size as to represent the volume of the valve passages, etc. 15 Thus at each operation enough mixture is drawn through and formed into gas to charge the cylinder.

What we claim is:—

1. The process of producing gas from carbonaceous material which consists in continuously generating in a chamber, in the presence of air at substantially atmospheric pressure, a zone of high temperature gases, passing into said chamber carbonaceous material with an elastic fluid medium, during such generation of the high temperature zone, and withdrawing the produced gases by suction from the chamber, the high temperature zone being between the place of 25 admission of the carbonaceous material and the place of the suction of the produced gases.

2. The process of producing gas from liquid hydro-carbons, which consists in continuously generating in a chamber in the presence of air at substantially atmospheric pressure, a zone of high temperature gases, passing into said chamber hydro-carbon with an elastic fluid medium during such generation of the high temperature zone, and withdrawing the produced gases, by suction, from the chamber, the high temperature zone being between the place of admission 40 of the hydro-carbon and the place of suction of the produced gases.

3. The process of producing gas from liquid hydro-carbons, which consists in di-

recting a burner flame into a chamber in the presence of air at substantially atmospheric pressure to internally heat the chamber, 50 passing hydro-carbon with an elastic fluid medium into the chamber below the level of the burner flame and withdrawing, by suction, the gases from the chamber above the level of the burner flame. 55

4. The process of producing gas from liquid hydrocarbons which consists in heating the hydrocarbon, separating the lighter from the heavier constituents thereof, burning a heavier portion of the oil in a chamber to heat the same internally and continuously, passing a lighter portion of the oil into the chamber with an elastic fluid medium, and drawing the same through the heated portion of the chamber and out 60 of the chamber by suction applied to the chamber. 65

5. The process of producing gas for a variable supply, which consists in directing a burner flame into a chamber, in the presence of air at substantially atmospheric pressure, to internally heat the chamber, passing oil with elastic fluid medium into said chamber, drawing produced gas from the chamber to a variable consuming means, 70 and controlling the oil supply in accordance with the demands of the consuming means. 75

6. The process of producing gas from liquid hydrocarbons which consists in causing the flames from a plurality of burners 80 to impinge in opposition, within a chamber, to form a zone of high temperature, supplying hydrocarbon with an elastic fluid to the chamber below said zone, and drawing off the produced gas above said zone. 85

In testimony whereof, we have hereunto set our hands at Los Angeles, California, this 15th day of October 1907.

WARREN H. FROST.
JOSHUA J. NIX.
